VALUE SETTING AND REGISTERING
MECHANISMAlva G. Russell, Stamford, Conn., assignor to
Pitney-Bowes, Inc., Stamford, Conn., a corpo-
ration of Delaware

Application April 28, 1948, Serial No. 23,847

3 Claims. (Cl. 235--101)

1 This invention relates to value printing and registering mechanism, and more particularly to value setting and actuating means as provided in a postage printing and registering device more commonly known as a postage meter.

In a postage meter selected values may be set up in type wheels within a printing drum, and through actuator means, the value set will be registered accumulatively in numeral register wheels when a printing cycle of operation is effected. According to the present invention, improved means is provided for type wheel and register actuator setting, also an actuator drive which will provide a continuous drive of the register numeral wheels during a printing cycle while the settable and setting elements remain in an operative relation.

It is one object of the invention to combine with a rotary printer, an improved type wheel and register actuator setting means, and to include therewith a register actuator gear structure, wherein each of a plurality of gears represents a type wheel value, and arranged same so as to effect the continuous drive of each of said gears and a selected register numeral wheel during an entire printing cycle of operation.

It is another object to provide a numeral register wheel actuator, wherein each numeral value of the register wheel has a gear associated therewith, and to effect a variable drive for said gears, whereby each gear will rotate a distance agreeing with the value it represents, and to provide a settable geared drive between said actuator and register wheel, whereby the value selected will be geared from the actuator gear to the register wheel.

It is another object of the invention to provide non-rotative and rotative members which are axially aligned and longitudinally adjustable, and which include a toothed rack portion, geared to type wheels in a printing drum, and a further toothed rack portion geared to a settable element, to thereby provide for type wheel setting and numeral wheel actuator control setting, and which will permit a printing cycle of operation while the said members remain in operative engagement.

With the above and other objects in view, which will appear as the description proceeds, the invention resides in the combination and arrangement of parts and in the details of construction hereinafter described and claimed, it being understood that various changes in the precise embodiment of the invention herein disclosed may be made within the scope of what is claimed.

2 without departing from the spirit of the invention.

A preferred embodiment of the invention is illustrated in the accompanying drawings, 5 wherein:

Fig. 1 is a side view showing the mechanism in a postage printing and metering unit with parts broken away and parts in section;

Fig. 2 is a plan view of Fig. 1, with parts 10 broken away and parts in section;

Fig. 3 is an end sectional view taken along the line 3--3 of Fig. 2;

Fig. 4 is a fragmentary end sectional view 15 taken along the line 4--4 of Fig. 1;

Fig. 5 is a fragmentary sectional view through the printing drum and taken along the line 5--5 of Fig. 2;

Fig. 6 is a detail view showing nested and set- 20 table sleeve and type setting members;

Fig. 7 is an enlarged sectional view of the joint 25 between the rotative and non-rotative sleeve members; and

Fig. 8 is a cross sectional view through the actuator gear unit and drive, taken along the 30 line 8--8 of Fig. 3.

A shaft 11 has a printing drum 13 fixed thereon and is supported by end walls 12--12 of a frame 10. Type wheels 14 are rotatively mounted on a shaft 15, within the printing drum 13, and the shaft 15 is supported by a bracket 16. Each type wheel 14 has a pinion 17 fixed thereto.

Registering mechanism, generally indicated at 35 18, is rotatively supported on a shaft 19, carried by the walls 12--12, and comprises differentially controlled numeral wheels 21, each of which is adapted to be independently driven in a manner disclosed in patent application Serial No. 760,590.

In a postage printing and registering device, 40 the type wheels are adapted to be adjusted to a value which it is desired to print, and while said adjustment is effected, register actuator mechanism is adapted to be set for subsequent use in the registration of the set value during a printing cycle of operation. In the present structure, improved mechanism is provided for effecting both type wheel setting and actuator setting, and improved actuator means is provided which will effect the continuous drive of the register during the printing cycle.

The mechanism for accomplishing the above, 45 in the order named, includes a sleeve structure, best shown in Fig. 6, which comprises a non-rotative sleeve 22 and a rotative sleeve 23. Said sleeves are positioned about the drum shaft 11 and have their abutting ends joined in the man-

ner indicated in Fig. 7, to provide for longitudinal movement of both sleeves and rotative movement of one sleeve relative to the other. Said joint includes a peripheral flanged and grooved portion 24—24a in the sleeve 23, which is adapted to be joined with an internal flanged and grooved portion 20—20a in the non-rotative sleeve 22. Sleeve 22 has a part of its joint portion cut back a distance of 180°, as indicated at 22b, to permit the assembly thereof with the rotative sleeve 23. Said sleeve 23 further includes a projecting segmental portion 25 which has rack teeth 26 along one edge, as indicated in Figs. 2, 5 and 6. Said teeth 26 are adapted to be geared to the type wheel pinion 17 by means of intermediate gearing, generally indicated at 21, Figs. 2 and 5. A further segmental extension 28 is provided on the non-rotative sleeve 22, which also is provided with rack teeth 29.

For the purpose of simplifying the illustration, the disclosure has been limited to two type wheels and elements associated therewith, but it will be understood that these may be increased as desired. As best shown in Fig. 6, the two sleeve member assemblies are shown nested one within the other and are mounted on a suitable supporting sleeve 31, which latter sleeve is supported on the shaft 11. Further, in Fig. 6, it will be noted that the rack toothed segment portions 25 extend into the printing drum 13 and will therefore move with the printing drum during a printing cycle of operation.

Longitudinal adjustment of the sleeve structure 22—23 is provided by means of segmental gears 32, which gears are mounted on a shaft 33, carried by supports 34, within the frame 10. Setting levers 35 are also carried by the shaft 33 and are joined with the segment gears 32 in such manner that when said levers 35 are rocked, the segment gears 32 will effect longitudinal motion of the toothed rack portions 28, the sleeves 22—23 and type wheel setting rack portions 25. The setting levers 35 are joined with their respective gear segments 32, as indicated in Fig. 3.

As thus far described, the structure relates particularly to the adjustment of the type wheels.

The register actuating mechanism and the means for adjusting same in agreement with the type wheel settings will now be described. A plurality of gears 37 of equal diameter are rotatively mounted upon a shaft 38, which shaft is supported within the walls 12—12 of the frame 10. Each gear 37 represents one digit value of the type wheels and each gear is adapted to be driven a proportionate part of a revolution in accordance with the value it represents. In other words, the gear representing the value "1" will move a distance representing that value, while the gear representing the value "9" will rotate a distance nine times the distance of the gear representing the value "1." To produce this result, each of the gears 37 has a gear 39 of variable diameter joined therewith, and the gears 39 are driven by a group of gears 41 of varying diameters. Said latter gears 41 will produce the proper drive ratio for each gear 37 in accordance with the value it represents. The gears 41 are fixed to a shaft 42 which has a gear 43 secured thereon. By means of a reduction gear drive 44, best indicated in Figs. 1, 2 and 4, a drive for the gear 43 is effected from a pinion 45 fixed to the drum shaft 11, and is so arranged that the gears 37 are continuously driven during the full revolution of the printing drum. This latter condition adds an important contribution

to the operation of a postage metering device, in that the continuous drive of the actuator gears during the complete printing cycle permits far slower and uninterrupted operation than has ever been attained before in a postage meter.

A cyclical drive is provided for the drum shaft 11 through a clutch connection 14a with a power drive of a metered mail machine in a manner disclosed in Patent 2,141,119.

A settable pinion 46 is adapted to be longitudinally adjusted along a splined shaft 47, which shaft is rotatively mounted within the end walls 12—12. Said pinion 46 has a grooved hub portion 48, which is adapted to be engaged by a yoke 49. The yoke 49 extends upwardly from a sleeve 50, which sleeve is adapted to slide on a shaft 40 and has a rack toothed portion 51 along the lower edge thereof. A second settable pinion structure indicated generally at 46a, Fig. 3, is provided for the second denominational value, but is otherwise the same as that just described. By observation of Fig. 3, it will be seen that additional settable pinion structures could be conveniently positioned around the actuator gears 37.

A gear segment 52 is fixed to a tube 53, which tube also has a gear segment 54 fixed to its other end. There are as many gear segment and tube assemblies as there are setting levers, which assemblies are nested as shown in Fig. 3, and are supported on a shaft 55, carried by brackets 56—56. The gear segments 54 are adapted to mesh with the segments 32. Therefore, when adjustment of a setting lever 35 is effected, the gear segments 32, 54 and 52 associated therewith, will be rocked to thus adjust the rack 51 and pinion 46 longitudinally along the shaft 47, relative to the gears 37.

A drive is provided between each splined shaft 47 and associated register numeral wheels 21, which drive comprises a pinion 56, fixed to each of said splined shafts 47, and intermediate gearing, generally indicated at 57. Said intermediate gearing includes gears 57a rotatively mounted on shaft 38, and compound gear members 57b, 57c, mounted on a shaft 58. The intermediate gears 57c mesh with associated gears 21a, which form a part of the register numeral wheel drive. Transfer from a numeral wheel of lower to a higher order is effected by means of Geneva pinions 59.

Aligner means is provided, as best shown in Figs. 2 and 3, wherein an aligner bar 60 extends downwardly from the bridging end of a U-shaped element. Said element is pivotally mounted on a rod 61 and has its arms turned downwardly as at 62, which arms are joined by a short rod 63. A vertically disposed bar 64 is pivoted at its lower end as at 65, near the base of the frame 10, and has a roller 66 thereon. Said roller is urged into a groove 67 of a cam member 68 on the drum shaft 11, by means of a spring 69. The upper side edge is normally maintained against the short rod 63 by means of a spring 71. When therefore, the drum shaft is rotated, the roller 66 is forced out of the notch 67 to thereby rock the bar 64, and, through contact with the rod 63, will rock the U-shaped element in a counter-clockwise direction to remove the aligner bar 60 from engagement between the teeth of the actuator gears 37. At the completion of a cycle of operation, the roller 66 will again be urged into the notch 67, thus effecting the return of the aligner bar 60 to a tooth aligning position. This will also effect alignment of the numerals 70 on the numeral wheels 21.

During each printing cycle of operation therefore, each actuator gear 37 will be driven a variable distance to effect the drive of predetermined numeral wheels 21 a distance determined by the adjusted position of the pinions 46 relative to selected gears 37, and the drive will be continuous throughout the entire cycle.

Having described the invention what is claimed is:

1. A valuating drive for the totalizer of a postage meter comprising a pair of parallel shafts, one of which is a drive shaft and the other of which is an idle shaft; and pairs of meshing unmutilated valuating gears, one gear of each pair mounted on said drive shaft to be driven thereby and the other being mounted for rotation on the idle shaft, the gears on one shaft having decreasing pitch diameters and the gears on the other shaft having increasing pitch diameters depending on the value represented by each pair, the total of the pitch diameters of each pair being the same as that of each other pair, each pair of meshed gears having an actuator gear driven by it, all said actuator gears having the same pitch diameter, the ratio of each pair of gears with its respective actuator gear being different from the others and the ratios being proportional to the values of 1 to 9 inclusive.

2. A valuating drive for the totalizer of a postage meter comprising a pair of parallel shafts, one of which is a drive shaft and the other of which is an idle shaft; and pairs of meshing unmutilated valuating gears, one gear of each pair mounted on said drive shaft to be driven thereby and the other being mounted for rotation on the idle shaft, the gears on one shaft having decreasing pitch diameters and the gears on the other shaft having increasing pitch diameters depending on the value represented by each pair, the total of the pitch diameters of each pair being the same as that of each other pair, each pair of meshed gears having an actuator gear driven by it and coaxial with the idle shaft, all said actuator gears having the same pitch diameter, the ratio of each pair of

gears with its respective actuator gear being different from the others and the ratios being proportional to the values of 1 to 9 inclusive.

3. A valuating drive for the totalizer of a postage meter comprising a pair of parallel shafts, one of which is a drive shaft and the other of which is an idle shaft; and pairs of meshing unmutilated valuating gears, one gear of each pair mounted on said drive shaft to be driven thereby and the other being mounted for rotation on the idle shaft, the gears on one shaft having decreasing pitch diameters and the gears on the other shaft having increasing pitch diameters depending on the value represented by each pair, the total of the pitch diameters of each pair being the same as that of each other pair, each pair of meshed gears having an actuator gear driven by it and coaxial with the idle shaft, all said actuator gears having the same pitch diameter, the ratio of each pair of gears with its respective actuator gearing being different from the others and the ratios being proportional to the values of 1 to 9 inclusive, said pairs of gears and said actuator gears being supported solely by said pair of parallel shafts.

ALVA G. RUSSELL.
